UNITED STATES PATENT OFFICE.

WILLIAM GRAY, OF HARTFORD, CONNECTICUT.

DESIGN FOR A TRANSMITTER-POST FOR TELEPHONES.

SPECIFICATION forming part of Design No. 23,825, dated November 27, 1894.

Application filed August 30, 1894. Serial No. 521,753. Term of patent 14 years.

To all whom it may concern:

Be it known that I, WILLIAM GRAY, a citizen of the United States, residing at Hartford, in the county of Hartford and State of Connecticut, have invented and produced a new and original Design for a Transmitter-Post for Telephones, of which the following is a specification, reference being had to the accompanying drawing, showing a part thereof.

10 The figure is an outline view in side elevation showing my design.

The leading feature of my design consists in a standard *a* having a broadened or flaring base *b*. This standard extends from the base 15 and is curved to one side the upper part being extended in two branches, a lower branch *c* and an upper branch *d*. The upper branch

d bears the transmitter *e* extending over and beyond the lower branch *c* the transmitter having a widened or flaring end, and extending downward from the transmitter *e* to the lower branch *c* is an extension *f*. The branches from the standard *a* and the transmitter and extension secured to the upper branch meeting the lower branch inclose an open space, as shown in the drawing.

20 What I claim is—

25 The design for a transmitter post substantially as herein shown and described.

WILLIAM GRAY.

Witnesses:

ARTHUR B. JENKINS,
J. STERN.
